F. N. LEWIS

FOREHEAD STRAP

Filed March 2, 1923

INVENTOR.
Florence N. Lewis
BY
George C. Henrichs
ATTORNEY.

UNITED STATES PATENT OFFICE.

FLORENCE N. LEWIS, OF NEW YORK, N. Y.

FOREHEAD STRAP.

Application filed March 2, 1923. Serial No. 622,301.

To all whom it may concern:

Be it known that I, FLORENCE N. LEWIS, a citizeness of the United States, residing at New York, county of New York, and 5 State of New York, have invented certain new and useful Improvements in Forehead Straps, of which the following is a specification.

This invention relates to improvements 10 in appliances for facial treatment or massage, and it is the principal object of the invention to provide a strap for the treatment of the forehead to remove wrinkles therefrom, etc., and to be used in connection with an astringent or without the same.

Another object of the invention is the provision of a bandage or strap of this character which can be readily applied to the 20 head and removed therefrom and securely fastened thereto for intimately holding the astringent to the skin to be absorbed thereby and to contract the soft organic tissues of the forehead and remove all wrinkles and 25 furrows therefrom to produce a smooth skin.

A further object of the invention is the provision of a forehead strap which can be readily adjusted to any size of head.

These and other objects of my invention 30 will become more fully known as the description thereof proceeds and will then be specifically pointed out in the appended claim.

In the accompanying drawing, forming a 35 material part of this disclosure:

Figure 1 is a plan view of my appliance constructed according to the present invention, seen from its inner side.

Figure 2 is an edge view of the same.

40 The device comprises a comparatively wide central part 10, preferably made of rubber, or any other suitable material with the ends of which are integrally made or at-

tached thereto in any suitable manner, straps 11 and 12 each provided with a plurality 45 of perforations 13 through which the attaching bands 14 are drawn, as illustrated.

In approximately its middle, near the lower part thereof, the central part 10 has a strengthened pad 15, the inner margin of 50 which is curved inwardly as at 16, while its lower edge is outwardly curved as at 17.

It will be clear that the astringent spread over the skin of the forehead, or a pad 55 of absorbent cotton saturated with such an astringent will be firmly kept in place under the bandage when the same is secured to the forehead by means of straps 11 and 12 and bands 14, and the strengthened part 15 will snugly fit against the part of the forehead between the eyebrows to treat the wrinkles formed between the same. The forehead strap may also just as well be used without the astringent to produce the desired results by repeated treatments. 60

Changes may be made in the general arrangement and in the construction of the minor details of my invention without deviating from the scope and spirit thereof. 65

What I claim as new, and desire to secure 70 by Letters Patent is:

A rubber forehead strap comprising a comparatively wide central part, a pair of rubber bands integral with the ends of said central part, each of said bands provided 75 with a plurality of spaced juxtaposed perforations, a central strengthened part in said central part, having an inwardly curved upper edge and an outwardly curved lower edge, and bands adapted to be drawn 80 through the perforations of said rubber bands for securely attaching said device to the forehead of a person.

In testimony whereof I have affixed my signature.

FLORENCE N. LEWIS.
